UNITED STATES PATENT OFFICE.

WILLIAM T. JAMES, OF CHICAGO, ILLINOIS.

CHAIN.

No. 856,529.

Specification of Letters Patent.

Patented June 11, 1907.

Application filed September 4, 1906. Serial No. 333,038.

To all whom it may concern:

Be it known that I, WILLIAM T. JAMES, a citizen of the United States, residing at Chicago, in the county of Cook and State of Illinois, have invented certain new and useful Improvements in Chains, of which the following is a specification.

My invention relates to chains, and especially to that type known as conveyer chains, and has for its objects; to provide an improved chain of inexpensive construction having an antifriction joint; to provide a chain having a pivot joint in which the bearing surfaces shall be very hard and dense and yet which shall be so constructed as to avoid brittleness and possess a maximum toughness; to provide a chain with a hardened bearing edge so constructed that slipping and impact tending to destroy the edge is avoided; and to provide a chain in which the pivoting surfaces are inclosed and protected from injury and dirt. These and other objects are accomplished by my invention one form of which is illustrated in the accompanying drawings in which,

Figure 1 is a plan view of one form of chain.

Figure 2 is a side elevation of the chain of Figure 1,

Figure 3 is a section through Figure 1 on the line 111—111,

Figure 4 is a plan view of a single link of another form of chain,

Figure 5 is a side elevation of the upper side member shown in Figure 4,

Figure 6 is a side elevation of the lower side member shown in Figure 4,

Figure 7 is a plan view of a section of chain composed of the links as shown in Figure 4, and

Figure 8 is a side elevation of the chain of Figure 7.

Referring first to the form of chain as shown in Figures 1, 2 and 3, it will be seen that each of the links is composed of two opposing side members 1—1, which side members are spread apart at the ends 2—2 and at the other ends 3—3 are secured together by the shield 4 (Figure 3), which shield extends about the pivot points of the links and serves the double function of a connecting or tie member and of a protector for preventing injury to the pivot members and excluding dirt. Securely riveted to the ends 2, 2 is the pivot block 5 which block is made circular in general cross section and has a V shaped bearing recess 5' extending throughout its

length. The inside ends 3 are provided with clearance spaces 6 to permit of the oscillation of the pivot block 5 when the chain passes over its sprocket and a knife edge bearing block 7 is provided at the side of the clearance space 6, which block is riveted securely in the ends 3, 3 and coacts with the V shaped bearing recess in the pivot block 5. It will be seen that the knife edge pivoting provides an antifriction joint, and that as the knife edge on the bearing block 7 engages a V shaped recess on the bearing block 5 there is no danger of any lateral slipping between the engaging surface, which slipping and the jar incident thereto ordinarily rapidly reduces the limited bearing surfaces. This is especially important in the case of hardened bearing points for the reason that such points are apt to be more brittle and the slipping and the jar tends to break off the pivotal edges. It will also be noted that the amount of bending at the pivot may be regulated by the difference in angle between the recess in the pivot block 5 and that of the projection of bearing block 7, as the flat surfaces of such recess and projection will contact when the two parts attain their maximum angles to each other. The links are also provided intermediate their ends with rollers 9 which are designed primarily to engage the teeth of the driving sprocket thereby removing the driving strain and wear incident to the engagement of the pivotal parts of the chain with the teeth of the sprocket. These rollers not only serve this purpose but also decrease the resistance of the chain when dragged along a guide or other supporting surface, as by means of such rollers the sliding friction is obviated and rolling friction substituted therefor.

A modified form of chain is shown in Figures 4 to 8 which chain while resembling the one of Figures 1 to 3 in a certain extent as far as the pivot bearing is concerned is different therefrom in that the pivot block and the bearing block are both carried by, and integral with one of the side members of the chain, and that the bearing block is hollow and adapted to receive the pivot block of a succeeding link. Referring first to Figures 4 to 6 it will be noted that each link is composed of two side members 10 and 11, the member 10 carrying integral therewith the pivot block 12 and the bearing block 13, while the member 11 is simply a flat section bent outward at one end as indicated in the

drawing. The member 10 will ordinarily be a cast member and is provided around its edges with the strengthening rib 14 as indicated in Figure 8. The pivot block 12 is 5 adapted to extend through a hollow bearing block on the succeeding link corresponding to the bearing block 13 and such pivot block is of the shape indicated in Figure 5 and has at its bearing side a recess 15 corresponding to the V shaped recess in the pivot block 5 of Figures 1, 2, and 3, but less acute. This pivot block 12 is provided at its central bearing portion with an insert 16 of hardened material adapted to bear against the pivot 10 point of the bearing block 13. The side member 11 is secured to the pivot block 12 by means of a cotter passing through the hole 17 in the end of the pivot block. The bearing block 13 is, as indicated in Figures 4 15 and 5, hollow with a space 13' sufficiently large to provide clearance for a bearing block similar to 12 which it is adapted to receive and such bearing block has at its forward end a projection 18 provided with an insert 19 for engaging the insert 16 on the pivot block 12. By thus providing a hollow bearing block receiving the pivot block, the pivot bearing is completely inclosed thereby protecting it from all chance of injury and from 20 dust and dirt. As shown, the bearing block 13 is provided with a shoulder 20 for engaging against the side of the member 11 thereby spacing such side member 11 a fixed distance from the side member 10. The side member 25 11 is provided at one end with an opening 21 of a size to exactly fit the pivot block 12, and the other end is provided with an opening 22 of sufficient size to exactly fit the end of the bearing block 13. The use of the hardened 30 inserts 16 and 19 of the pivot block and bearing block respectively is advantageous in that it prevents a too rapid wearing away of the restricted bearing surface and these bearing inserts are protected from the damage 35 usually incident to hard brittle bearing surfaces because of their insertion in the body of the metal of the blocks, which location stiffens and supports the hard and brittle metal of the inserts. It is thought that 40 the manner in which the links are assembled and secured together will be obvious from an inspection of the assembled views of Figures 45 7 and 8.

It will be apparent that various modifications of the broad idea involved are possible without departing from the spirit of the invention. The bearing surfaces may be changed by modifying the style of inserts and also by modifying the degree of the angle of the recess in the pivot block and the degree of the angle of the projection on the bearing block, it being only necessary that such parts be so arranged that there is no possibility of side-wise slipping when lateral pull is applied to

the chain. Changes along these lines and 65 others apparent to those skilled in the art are comprehended by my invention and are intended to be covered by the claims.

Having thus described my invention and illustrated its use, what I claim as new and 70 desire to secure by Letters Patent, is the following:

1. In combination in a chain, a link comprising side members and a bearing member having a V shaped recess longitudinally 75 thereof, and a second link comprising side members and a bearing member having a V shaped projection for engaging the V shaped recess in the first bearing member, the angle of the projection being more acute than that of the recess and the recess of such depth that the sides thereof constitute a stop for limiting the relative rotative movement of the links.

2. In combination, a link comprising a side member provided at one end with a pivot block and at the other end with a hollow bearing block, and a second side member adapted to engage the pivot block and bearing block.

3. In combination, a link comprising a side member having rigidly secured to one end a pivot block and to the other end a hollow bearing block, and a second side member adapted to engage the pivot block and bearing block.

4. In combination, a link comprising a pair of side members and a pivot block rigidly secured to one member and removably secured to the other member, and a second link comprising a pair of side members and a hollow bearing block adapted to coact with the pivot block secured rigidly to one member and removably to the other member.

5. In combination in a chain, a link comprising side members and a bearing member having a recessed portion provided with a bearing insert, and a second link comprising side members and a bearing member having an edge provided with a bearing insert for engaging the insert in the first bearing member.

6. In combination in a chain, a link comprising side members and a bearing member having a V shaped recess longitudinal thereof provided at the apex with a bearing insert and a second link comprising side members and a bearing member having a V shaped projection provided with a bearing insert at its point for engaging the insert in the first bearing member.

In testimony whereof I have hereunto signed my name in the presence of the two subscribed witnesses.

WILLIAM T. JAMES.
